Primary Examiner — Marianne Pandozzi*Assistant Examiner* — Jae Liang(74) *Attorney, Agent, or Firm* — Jeffrey A. Proehl; Woods, Fuller, Shultz & Smith, PC(57) **CLAIM**

The ornamental design for a beverage container, as shown and described.

DESCRIPTION

FIG. 1 is a perspective view of a beverage container of my new design;

FIG. 2 is a front elevational view of the beverage container; FIG. 3 is a rear elevational view of the beverage container; FIG. 4 is a left side elevational view of the beverage container, the right side elevational view being a mirror image thereof;

FIG. 5 is a top plan view of the beverage container; and, FIG. 6 is a bottom plan view of the beverage container. The broken lines depict portions of the device that form no part of the claim.
